UNITED STATES PATENT OFFICE.

THOMAS CHARLES BROMLEY AND WALTER CAVERS, OF LEICESTER, ENGLAND, AS-SIGNORS TO MELLOR BROMLEY & CO. LIMITED, OF MINOTAUR WORKS, LEICESTER, ENGLAND.

CIRCULAR RIB-KNITTING MACHINE.

Application filed August 10, 1921. Serial No. 491,112.

To all whom it may concern:

Be it known that we, THOMAS CHARLES BROMLEY and WALTER CAVERS, both subjects of the King of Great Britain, residing at 5 Leicester, in the county of Leicester, England, have invented new and useful Improvements in or Relating to Circular Rib-Knitting Machines, of which the following is a specification.

10 This invention relates to circular rib knitting machines and concerns more especially those of the type wherein the needle cylinder and dial rotate.

The object of the invention is to provide 15 in such machines improved means for driving the dial and maintaining proper co-relation between dial and cylinder needles with possibility of adjustment.

An important feature of the present invention is a construction of the dial driving means which enables the dial and associated parts to be raised above the needle cylinder from operative position such as for allowing 20 clear access to the cylinder. The upward and downward movement of the dial from and to its working position takes place without disturbing the circumferential co-relation of the dial and cylinder needles as will be hereinafter explained.

25 According to the invention the dial is movable up and down on a central spindle and is rotated by a vertical rod which passes slidably through a rotatable frame carried by the said spindle and located within the needle cylinder, said frame being driven by the contact therewith of dogs on the inside of the cylinder.

30 A plurality of driving dogs are provided and in order to ensure the proper contact of each dog with the driven rotating frame, the latter is furnished with adjustable rollers, the tubular fabric passing down between 35 said dogs and rollers.

To enable the invention to be clearly and 40 readily understood, a convenient practical embodiment of the same is illustrated in the accompanying drawings, wherein:—

45 Figure 1 is a vertical section of the upper part of a circular multiple feeder rib knitting machine provided with the improved dial arrangement.

50 Figure 2 is a sectional plan taken on the line *a—a* of Figure 1.

Figures 3 and 4 (drawn to a larger scale)

show alternative forms of the adjustable 55 rollers on the driven frame.

Throughout the drawings like parts are designated by the same reference characters.

Referring to Figure 1, the bed of the machine is represented at 1 having a suitable 60 recess in which is rotatably mounted a carrier wheel 2 to which the needle cylinder 3 is attached, the carrier wheel being driven by a bevel wheel 4 at the driving shaft 5. This is the usual practice and forms no part 65 of the present invention which concerns the mounting and driving of the dial 6 as will now be described.

A vertical spindle 7 is supported in a stationary manner by a suitable overhead structure 8 carried by uprights 9 situated on opposite sides of the machine and attached in a rigid manner to the bed 1. The spindle 7 is arranged coincident with the vertical axis 70 of the needle cylinder 3 and dial 6 and has a screw threaded upper part 10. The spindle is held against rotation by any suitable means and its lower end depends within the needle cylinder and has rotatably mounted thereon a spider or frame 11 having, as 75 shown in Figure 2, radial arms 12 which terminate near the inside wall of the needle cylinder 3.

Each arm 12 at its outer end is, according to one arrangement, fitted with a horizontally disposed eccentric stud 13 (see Figure 3) capable of being rotated for adjustment purposes and adapted to be fastened by a nut 14 thereon. Formed integrally with and eccentrically on each stud 13 is a 80 head or part 15 on which is mounted a roller 16 with which a corresponding lug or dog 17 projecting from the inner face of the cylinder 3 as shown in Figures 1 and 2 makes contact for driving the frame 11. By 85 rotation of the stud any of the rollers may be adjusted in relation to its driving dog.

According to an alternative arrangement, the roller 16 is mounted upon a concentric stud 13^a (Figure 4) capable of lateral adjustment by means of a set-screw 12^a in a hole 12^b in the arm 12, said hole being larger than the stud and the latter being fastened in position by a nut 14^a. In this case any of the rollers may be set up to its driving 90 dog by adjusting the stud 13^a.

Movable up and down on the central spindle 7 is a sleeve 18 (Figure 1) attached to

a transverse support 19 in a suitable manner so as to be held from rotation. On the lower part of this sleeve a hub 20 is mounted to rotate and is kept in position by a screwed lock ring 21. The dial 6 is secured in a suitable manner to the said hub and rotates with same. Above the dial 6, the dial cam cap 22 is attached by suitable means to an annular flange 23 on the sleeve 18 so as to remain stationary with the sleeve which, it will be understood, is held from rotation by the support 19 the ends of which are attached to brackets 24 capable of sliding movement up and down the before mentioned uprights 9 to which they may be clamped by means of screws 25. The uprights 9 are slotted vertically at 26 to enable the screws 25 to move up and down with the brackets 24. The bottom position of the brackets is determined by adjustable screws 9^a in the uprights 9 which screws enable the zero point or working height of the dial to be regulated in relation to the needle cylinder. 25 Working upon the screwed part 10 of the vertical spindle 7 is a handwheel 27 the boss 28 of which is internally threaded to fit the said screwed part and move up and down on same when rotated thereon. The boss 28 is also grooved circumferentially and engaged in the groove by plates 29 fastened to the support 19. When the screws 25 are slackened and the handwheel is rotated to move up the spindle 7, it raises the support 19 which by means of the sleeve 18 lifts the dial 6 and its cap 22 from the working position. In this manner the said dial and associated parts may be raised clear above the needle cylinder 3 when required as indicated by the dotted lines without disturbing the driven spider or frame 11 which remains in its working position on the lower end of the spindle 7. The support may be fastened in its raised position and also in the lower working position by tightening the clamp screws 25.

In order to transmit the drive from the driven frame 11 to the dial 6, the rotatable hub 20 which carries said dial has firmly secured to its underside a downwardly projecting rod or finger 30 (Figures 1 and 2). This rod passes down through an opening 31 formed through the outer end of an arm 32 on the frame 11 which arm has on opposite sides of the opening a set-screw 33. The set-screws are arranged to make contact with the rod 30 in the direct line of the drive the opening being made larger than the rod so that the latter can have a certain amount of adjustment relatively to the arm 33, effected by the set-screws, for the purpose of obtaining and maintaining the proper circumferential relationship between the dial needles 34 and cylinder needles 35.

When the dial 6 and associated parts are

raised and lowered in the aforesaid manner by rotation of the handwheel 27, the rod or finger 30 moves up and down through the opening 31 of the arm 32 without disturbing the circumferential co-relation of the needles. The tubular knitted fabric passes down between the rollers 16 and their driving dogs 17.

One advantage obtained by the arrangement herein described is that when the dial is raised and held in its highest position, the machine can be turned to cause knitting to take place upon the cylinder needles only, until all these needles have loops thereon and good fabric is being made. The dial may then be lowered to working position thus avoiding bad knitting at commencement which is common to other methods of running on.

What we claim then is:—

1. In a circular rib knitting machine, in combination, a rotary needle cylinder, a fixed spindle coincident with the axis of said cylinder, a dial rotatably mounted upon said spindle and movable up and down thereon; a rotary frame carried by said spindle and situated within the needle cylinder, dogs on the inside of said cylinder to drive said frame, and a rod fixed to and projecting from the dial and passing slidably through the rotary frame to transmit rotation from the latter to the dial.

2. In a circular rib knitting machine, in combination, a rotary needle cylinder, a fixed spindle coincident with the axis of said cylinder, a dial rotatably mounted upon said spindle and movable up and down thereon, a rotary frame carried by said spindle and situated within the needle cylinder, adjustable rollers on the frame, dogs on the inside of the needle cylinder for contact with the rollers to drive the frame, and a rod fixed to and projecting from the dial and passing slidably through the rotary frame to transmit rotation from the latter to the dial.

3. In a circular rib knitting machine, in combination, a rotary needle cylinder, needles therein, a fixed spindle coincident with the axis of said cylinder, a dial rotatably mounted upon said spindle and movable up and down thereon, needles in said dial, a rotary frame carried by said spindle and situated within the needle cylinder, dogs on the inside of said cylinder to drive said frame, a rod fixed to and projecting from the dial and passing slidably through the rotary frame to transmit rotation from the latter to the dial, and means to adjust the rod in the rotary frame for the purpose of maintaining proper co-relation between the dial and cylinder needles.

4. In a circular rib knitting machine, in combination, a rotary needle cylinder, a fixed screw threaded spindle coincident with the axis of said cylinder, a support, a hand-

wheel connected to said support and movable by rotation up and down the screw threaded spindle, a dial rotatably carried by said support, a rotary frame mounted upon said spindle and situated within the needle cylinder, dogs on the inside of said cylinder to drive said frame, a rod fixed to and projecting from the dial and passing slidably through the rotary frame to transmit rotation from the latter to the dial, and means to adjust the rod in the rotary frame for the purpose described.

5. In a circular rib knitting machine, in combination, a rotary needle cylinder, a screw threaded spindle arranged coincident with the axis of said cylinder, a structure to support said spindle in a stationary manner, a transverse support movable up and down the screw threaded spindle and engaging the said structure at each end, a handwheel fitting said screw threaded spindle and con-

nected to the transverse support to raise and lower same when rotated on the spindle, a sleeve movable up and down the spindle and attached to the transverse support, a 25 flange on said sleeve, a dial cam cap attached to said flange, a hub rotatably mounted on said sleeve, a dial attached to said hub, an armed frame rotatably mounted on the spindle and situated within the needle cylinder, adjustable rollers on said frame, dogs on the inside of the needle cylinder to make contact with the rollers for driving the frame, a rod attached to and projecting from the aforesaid dial said rod passing through an 30 arm on the rotary frame, and screws in said arm to adjust the rod in position in the rotary frame.

10. In testimony whereof we have signed our names to this specification.

THOMAS CHARLES BROMLEY.
WALTER CAVERS.
